UNITED STATES PATENT OFFICE.

LOUIS GASSARD, OF TORONTO, CANADA, ASSIGNOR TO THOMAS GABRIEL MASON, OF TORONTO, CANADA.

MACHINE DRILL-STOCK.

SPECIFICATION forming part of Letters Patent No. 711,563, dated October 21, 1902.

Application filed October 28, 1901. Serial No. 80,308. (No model.)

To all whom it may concern:

Be it known that I, LOUIS GASSARD, piano-maker, of the city of Toronto, in the county of York, in the Province of Ontario, Canada, 5 have invented certain new and useful Improvements in Machine Drill-Stocks, of which the following is a specification.

My invention relates to machine drill-stocks; and the object of the invention is to 10 devise a drill-stock which may be readily manipulated without undue exertion and which will be capable of perfect freedom of movement on the work to a limited extent, so as to bore any number of holes at any angle or 15 angles desired, either up or down, vertically, horizontally, or otherwise; and it consists, essentially, of a drill-stock rotatably held in a suitable holder, a series of pulleys supported in a suitable frame, a driving-belt 20 connecting said pulleys and rotatable stock with the main driving-pulley, and means for so adjusting the relative distances apart of the pulleys to vary the length and direction of the drive.

25 Figure 1 is a perspective view of my device. Fig. 2 is a cross-section on line *a b*, Fig. 1. Fig. 3 is a similar view on line *x y*, Fig. 1. Fig. 4 is a sectional elevation of the drill-stock.

30 In the drawings like letters of reference indicate corresponding parts in each figure.

A is the stock of the drill, provided with an annular frame *a*, provided with suitable handles *a' a''*.

35 B is a vertical spindle rotatably held within the frame *a* by the collar *b*. On the lower end of the spindle B is formed or secured the socket *b'* of the tool.

C is a pulley suitably secured on the spin- 40 dle B.

D is the main driving-shaft, and *d* is the main driving-pulley secured thereon.

E E are guide-bars secured to any suitable upright F.

45 *e'* represents guideways formed in the guide-bars E E.

G is a vertically-adjustable frame having depending from it the slide *g*, provided with side ribs *g'*, designed to fit into and have vertical movement within the guiding-grooves *e*. The frame G comprises the side boards

g² and *g³* and the connecting-bar *g⁴* at the back.

H H' are stationary idler-pulleys secured upon a suitable spindle *h*, supported upon 55 the side boards *g²* and *g³*, and H² is an idler-pulley secured on the spindle *h'*.

J is a vertical slot formed in the slide *g*, and *j* is a clamping-screw. *j'* is a clamping-block. By this means the frame G may be either 60 raised or lowered to any position and securely clamped to the upright F by the screw *j*.

I I' are cross-bars, to which is suitably secured the bar K.

k k' are guideways formed on each side of 65 the bar K, and K' is a weighted block provided with ribs *k²*, designed to enter and have vertical movement within the guideways *k k'*.

L is an idler-pulley journaled on the block K'.

70 M is an endless belt which passes from the driving-pulley D around the idler-pulley H², around the weighted idler L, over the idler H' to the pulley C, formed on the spindle of the drill-stock, then around the pulley H to 75 the driving-pulley D.

When it is desired to drill a hole in an article located at a distance from the machine, all that is necessary is to pull upon the stock of the tool, so as to pull the weighted pulley 80 L' upwardly in its guideways. When the hole is to be bored near the machine and the pulley is carried toward it, the belt becomes slack, which slackness is taken up by the pulley L falling in the guideways K K'. 85 When it is desired to drill a hole at an angle, the frame G is raised or lowered, so as to make the drive follow the position of the tool.

It will be found by having this machine that a great saving both of time and labor is 90 accomplished, as the old form of drills which were operated by hand tired the arm of the workman in a very short time. By this machine much more work can be accomplished in less time without causing much fatigue, as 95 both hands are free to force the tool into the wood, and thus a hole may be drilled much more quickly.

What I claim as my invention is—

1. The combination with a hand-drill having an operating-pulley, of means for driving the same consisting of a main drive-pul-

ley, a vertically-adjustable frame, carrying two pulleys in the rear and a third pulley in the front thereof, an idler-pulley arranged beneath the pulleys on said frame, said idler-pulley being weighted and having a limited vertical movement, and a driving-belt extending from the main driving-pulley over the front pulley of said adjustable frame, down under the idler-pulley and up over one of the two rear pulleys of the frame, thence to the hand-drill, then back over the second rear pulley of the frame to the main driving-pulley, substantially as described.

2. In combination, in a hand-drill, a circular frame, a spindle extending therethrough, a pulley on said spindle, means for driving said pulley, a bit-holding stock at the bottom of the frame, a handle extending vertically from the frame and a second handle extending from the frame at an angle to the first handle, substantially as described.

3. The combination with the drill-stock, the pulley secured thereon, the frame therefor, the operating-handles secured thereto and the driving-pulley, of a supporting-bar, suitable guideways secured thereto, a vertically-adjustable frame provided with a depending stem designed to have vertical movement within said guideways, a series of pulleys journaled therein, means for securing said frame in any desired position, supplemental guide-bars secured to said support-

ing-bar, a block provided with a pulley and slidably held in the supplemental guide-bars and a driving-belt passing around the pulley 35 on the drill-stock, over said idler-pulleys and under the pulley on the slidable block to the driving-pulley as and for the purpose specified.

4. The combination with the drill-stock, 40 the pulley secured thereon, the supporting-frame therefor, the handles secured thereto, of a supporting-bar, suitable guideways secured thereto, a vertically-adjustable frame provided with a depending stem having a vertical slot therein and designed to have vertical movement in said guideways, a clamping-screw designed to pass through said slot into the supporting-bar, a cross-spindle h supported on said frame, idler-pulleys H and H' 45 journaled therein, a cross-spindle h' also supported on said frame, an idler-pulley supported thereon, supplemental guide-bars secured to said supporting-bar, a block provided with a pulley and slidably held in the 50 supplemental guide-bars and a driving-belt passing around the pulley on the drill-stock over said idler-pulleys and under the pulley on the slidable block to the main driving-pulleys as and for the purpose specified.

LOUIS GASSARD.
